WELL DRILLING APPARATUS

**Dennis L. Driscoll, Los Angeles, Calif., assignor
to Lawrence F. Baash, Los Angeles, Calif.**

Application March 4, 1936, Serial No. 67,080

18 Claims. (Cl. 24—263)

This invention relates to well drilling apparatus and relates more particularly to a rotary table bushing and slips therefor. A general object of this invention is to provide an improved rotary table bushing and slip assembly that is particularly effective and long wearing.

Another object of this invention is to provide a practical rotary table bushing and slip assembly in which the slips all have extensive and equal seating engagement with the bushing and have uniform gripping contact with the pipe or object handled. The extensive engagement of the slips in the bushing allows the slips to be of light construction and of substantial length.

15 Another object of the invention is to provide a master bushing for a rotary table that has inclined grooves or slots in its interior of uniform width throughout their lengths and slips shaped and proportioned to fit the slots whereby they
20 may have extensive continuous engagement with the walls of the slots while gripping the pipe and when in any vertical position they may assume while contacting the pipe. Heretofore it has been the usual practice to provide a round tapered
25 opening or a round opening of downwardly diminishing diameter in the bushing of a rotary table to receive the pipe gripping slips. When a bushing is provided with such a tapered opening there is only one vertical position in which the
30 slips have full cooperation with the walls of the bushing and when the slips assume different vertical positions as they often do when gripping a pipe, certain of the slips have only line contact or partial contact with the bushing. In the assembly of my invention the slips have full surface contact with the walls of the bushing slots regardless of the vertical positions they may assume when contacting the pipe.

Another object of this invention is to provide a slip receiving bushing for a rotary table having an opening of uniform dimensions throughout its length to more readily pass drill pipe protectors and other drilling equipment.

and other drilling operations.
Another object of this invention is to provide
an improved assembly of a rotary table bushing
and pipe gripping slips in which the slips cannot
foul one another and cannot turn or tilt laterally
in the bushing.

Another object of this invention is to provide
50 a rotary table bushing and slip assembly in which
all of the several slips have uniform gripping en-
gagement with the object or pipe throughout their
lengths to dependably grip the pipe without tend-
ing to distort it.

55 Another object of this invention is to provide

a rotary table bushing and slip assembly that embodies practical effective rests or cradles for the slips when they are removed from the bushing which cradles support the slip in positions for immediate insertion in the slots of the bushing. 5

Another object of this invention is to provide slips having simple and very inexpensive replaceable pipe engaging parts or liners whereby they may be readily reconditioned or adapted for the handling of pipe of various diameters. 10

The various other objects and features of my invention will be fully understood from the following detailed description of typical preferred forms and applications of my invention, throughout which description reference is made to the 15 accompanying drawings, in which:

Fig. 1 is a top or plan elevation of one form of assembly provided by this invention. Fig. 2 is an enlarged fragmentary horizontal detailed sectional view taken substantially as indicated by line 2—2 on Fig. 3. Fig. 3 is an enlarged fragmentary vertical detailed sectional view taken as indicated by line 3—3 on Fig. 1. Fig. 4 is a fragmentary elevation view of the upper portion of one of the cradles being a view taken substantially as indicated by line 4—4 on Fig. 3. Fig. 5 is an enlarged fragmentary horizontal detailed sectional view taken as indicated by line 5—5 on Fig. 3. Fig. 6 is a top or plan elevation of another form of assembly provided by this invention. Fig. 7 is a fragmentary vertical detailed sectional view taken as indicated by line 7—7 on Fig. 6. Fig. 8 is a fragmentary horizontal detailed sectional view taken as indicated by line 8—8 on Fig. 7. Fig. 9 is a perspective view of the inner side of one of the bushing sections of the form of the invention illustrated in Figs. 6, 7 and 8; and Fig. 10 is a top or plan elevation of still another form of assembly provided by the invention.

The form of the invention illustrated in Figs. 40 to 5, inclusive, of the drawings, includes generally, a bushing 10 for arrangement in a rotary table T and having slots 11 in its interior, slips 12 adapted to fit in the slots 11 to grip a pipe P or the like, and rests or cradles 13 for carrying the slips 12 when they are removed from the bushing 10. 45

The bushing 10 is what is usually termed a master bushing and is intended for arrangement in the opening 14 of the rotary table T. In the particular form of the invention being described the bushing 10 is round or cylindrical to fit the correspondingly shaped opening 14 of the table T. An annular outwardly projecting flange 15 is provided at the upper end of the bushing 10 to 55

fit in an enlargement or annular groove 16 in the upper end of the table opening 14 and to seat on a shoulder 16a in the opening 14. Lugs 17 project radially from the periphery of the flange 15 to fit bayonet slots 18 in the table T. Lock blocks 19 are inserted in the bayonet slots 18 to lock the lateral arms of the lugs 17 in the lateral portions of the slots 18. A rotary table of the general type just described having bayonet slots for receiving lugs on a bushing is fully described and claimed in my co-pending application entitled Rotary well drilling apparatus, filed November 11, 1935, Serial No. 49,175. It is to be understood that the bushing 10 being described may be shaped to fit any type of rotary table opening without departing from the invention. It is to be noted that when the bushing 10 is designed for use in the particular rotary table T illustrated that it has a cylindrical periphery throughout its length and, therefore, has a substantial and uniform wall thickness. The wall of the bushing 10 may be chambered and provided with suitable internal reinforcing webs 20.

The bushing 10 is preferably sectional to facilitate its insertion in the rotary table T. In the preferred construction the bushing 10 comprises two sections A and B of substantially equal extent as illustrated in Fig. 1 of the drawings. A central vertical opening 21 is provided in the bushing 10 to receive and pass the pipe P, tubing and other drilling equipment. It is a feature of the invention that the opening 21 is of uniform diameter or dimensions throughout its length, that is, the opening 21 has vertical walls and is not tapered or of downwardly diminishing capacity. This formation of the opening 21 permits the ready passage of drill pipe protectors and other devices through the bushing 10 which often interfere with the lower ends of the usual master bushings having central openings of downwardly diminishing diameter. In the particular form of the invention being described the opening 21 is round in cross section or is cylindrical, it being understood that the opening 21 of the bushing 10 may be polygonal, as illustrated in Figs. 6, 8, 9 and 10 of the drawings.

It is a feature of the invention that longitudinal or vertical slots 11 are provided in the wall of the opening 21 to receive the slips 12. The slots 11 are circumferentially spaced to provide for the spaced engagement of the slips 12 with the pipe P. In the drawings I have shown four equally spaced slots 11, it being understood that the bushing 10 may be provided with two slots, three slots or any desired number of slots 11, as desired. In accordance with the invention the slip receiving slots 11 are of uniform configuration and width throughout their lengths and are of substantial length to present extensive walls or surfaces for engagement by the slips 12. The opposite side walls of the slots 11 are parallel and are preferably vertical to provide for the easy insertion of the slips 12. In the particular form of the invention illustrated in Figs. 1 to 5, inclusive, of the drawings the inner walls 22 of the slots 11 are cylindrically concaved. These inner walls 22 of the slots 11 are inclined downwardly and inwardly to slidably receive the slips 12 and to provide for the wedging of the slips against the object or pipe P. The curvature of the inner walls 22 of the slots is the same throughout their lengths having a uniform radius of curvature. The above described shape and proportions of the slots 11 provide for the

full or extensive contact of the slips 12 with the slot walls. The slots 11 may extend from the face or upper end of the bushing 10 to the lower end of the bushing.

The slips 12 are provided to grip and suspend pipe P, tubing or other well drilling equipment extending through the bushing opening 21. The slips 12 are shaped and proportioned to properly fit and operate in the above-described slots 11. The pipe gripping slips 12 are elongate members 10 having flat parallel opposite sides 23 for cooperating with the side walls of the slots 11 and having cylindrically convexed rear surfaces 24 for shiftably bearing on the inner walls 22 of the slots. The curved or convexed surfaces 24 of the slips 12 are inclined downwardly and inwardly but have the same radius of curvature throughout their lengths to uniformly engage the walls 22. It is to be understood that when the slots 11 are polygonal or provided with flat inner walls the rear surfaces 24 of the slips 12 may be flat to have proper cooperation therewith. When seated in the slots 11 the slips 12 project into the bushing opening 21 to have suspending and gripping engagement with the object or pipe P.

The active faces or sides of the slips 12 may be suitably roughened or toothed to properly grip the object or pipe P. The invention, however, provides simple and particularly effective replaceable plates or liners 25 for the active sides of the slips 12. The liners 25 are secured to the inner or active faces of the slips 12 and are adapted to have direct engagement with the object or pipe P and thus assume the wear. The faces of the slips 12 are provided with longitudinal or vertical grooves 26 for receiving tongues or keys 27 on the liners 25. The lower walls 28 of the grooves 26 are inclined downwardly and outwardly. The lower ends 29 of the keys 27 are correspondingly inclined to have locking cooperation with the walls 28. The invention includes simple positive means for removably securing the liners 25 to the slips 12. Pins or rods 30 are inserted in transverse openings in the slips 12 and the keys 27 of the liners 25. The ends of the rods 30 may be riveted over whereby the rods are dependably held against displacement to form positive connections between the slips and the liners 25. The active faces of the liners 25 are cylindrically concaved to conform to the object or pipe P and are provided with wickers or teeth 31. The teeth 31 are adapted to have gripping and supporting contact with the pipe P and preferably face upwardly and inwardly. If desired the teeth 31 may be grooved vertically to more effectively resist relative rotation between the pipe P and the slip liners 25. The liners 25 may be replaced with liners of different thicknesses to adapt the slips 12 to handle pipe of different diameters.

The bodies of the slips 12 are preferably hollow or provided with chambers 32 to be light in weight. Reinforcing webs 33 may extend through the chambered interiors of the slips. Guide fingers 34 may be provided on the lower ends of the slips 12. The fingers 34 project from the lower ends of the slips 12 at their outer and side surfaces and slope or curve downwardly and inwardly. The mouths or upper ends of the bushing slots 11 may have downwardly and inwardly inclined guide walls or surfaces 35 to assist in entering and guiding the slips 12 in the slots 11. When entering the slips 12 in the slots 11 the fingers 34 may cooperate with the surfaces 35 to 75

guide the slips. The slips 12 usually project above the upper surface of the bushing 10 when engaging the pipe or object P. The invention provides means for preventing the slips 12 from falling through or from the slots 11. Stop lugs 36 project from the upper portions of the slip 12 sides 23 and are adapted to fit in recesses 36^a in the upper face of the bushing 10 to limit the downward and inward movement of the slips 12. The recesses 36^a are suitably shaped and proportioned to provide for the necessary play or movement of the slips 12.

The invention provides handles H on the slips 12 to facilitate their insertion in and removal from the slots 11. The handles H have forks or yokes 37 on their lower ends extending into recesses 37^a in the upper ends of the slips 12. Pivot pins 38 pivotally connect the forks 37 with the bodies of the slips 12. Cams or stop projections 9 may be provided on the forks 37 to limit the inward swinging of the handles H. The handles H include stems 39 extending upwardly from the forks 37 and lateral heads 39^a carried on the stems 39. If desired or found necessary the handles H of adjacent slips 12 may be connected whereby two of the slips may be handled simultaneously. The rear walls of the recesses 37^a may be engageable by the handles H to limit the outward and downward pivoting of the handles.

The rests or cradles 13 are provided to support or carry the slips 12 when the slips are withdrawn from the slots 11 and are operable to support the slips in positions where they are entirely clear of the bushing opening 21. A cradle 13 is provided on the bushing 10 for each slip 12. The cradles 13 are adapted to be removably secured to the upper end of the bushing 10 in radial alignment with the slots 11. Each cradle 13 includes a leg 40 having a substantially horizontal foot 41. Recesses 42 are provided in the upper side of the bushing 10 to receive the feet 41. Countersunk or flush plates 43 extend transversely across the upper ends of the recesses 42 and the feet 41 are adapted to be inserted under the plates 43. Clamp screws 44 are threaded through the plates 43 and are adapted to clamp against the feet 41 to securely hold the cradles 13 in place. The legs 40 project vertically from the feet 41 and have upwardly and outwardly inclined portions terminating in forks 45. Concave supports or saddles 46 are arranged on the inclined portions of the legs 40 to receive the slips 12. The saddles 46 are shaped and proportioned to properly receive the convex outer sides of the slips.

Means are provided for releasably supporting or holding the slips 12 in the cradles 13. The forks 45 on the upper ends of the legs 40 have flaring or V-shaped notches 47 adapted to receive handles H. When the slips 12 are raised into the cradles 13 the handles H may be swung downwardly so that their stems 39 are engaged in the notches 47. The heads 39^a of the handles H are adapted to engage against the forks 45 to hold the slips 12 in the cradles 13 in positions where they are entirely free of the bushing opening 21. This elevated or inoperative position of the slips 12 is illustrated in broken lines in Fig. 3. The handles H may be easily disengaged from the forks 45 to allow the slips 12 to enter or move downwardly into their respective slots 11.

In the use or operation of the assembly illustrated in Figs. 1 to 6, inclusive, of the drawings, the bushing 10 is normally arranged in the table T as illustrated in Fig. 1 of the drawings. When

it is desired to engage or suspend a pipe P passing through the bushing opening 21 the slips 12 are introduced into the slots 11 and allowed to fit downwardly therein until their liners 25 grip the pipe P. The operator or operators may readily disengage the handles H from the forks 45 to allow the slips 12 to slide downwardly in the saddles 46. The fingers 34 on the lower ends of the slips readily guide the slips into the slots 11. The slips are free to move downwardly in the slots 11 until the toothed inner sides of the liners 25 grip or contact the pipe P. The convex outer rear sides 24 of the slips 12 have full, even bearing engagement with the walls 22 of the slots 11 regardless of the vertical positions assumed by the slips 12 when they contact the pipe P. The engagement of the surfaces 24 with the slot walls 22 also maintains the active inner sides of the liners 25 vertical to properly grip the pipe P. The fit of the slips 12 in the slots 11 is such that the pipe is dependably gripped and supported. Due to the fact that each of the slips 12 has uniform and complete engagement with the inner wall 22 of its respective slot 11 the several slips have even or equal engagement with the pipe P to dependably grip the pipe without distorting it. The slips 12 engaging in the slots 11 are adapted to form a positive drive for the pipe P in the event it is desired to rotate the pipe. The flat parallel sides 23 of the slips 11 are adapted to engage the side walls of the slots 11 for the transmission of turning forces.

When the slips 12 are no longer required they may be easily pulled upwardly and outwardly to rest in the saddles 46. The handles H may be swung downwardly to engage the stems 39 in the notches 47 so that the slips are held in the cradles 13. The slips 12 are very easy and convenient to manipulate and are light in weight. The cradles 13 may be easily disengaged from the bushing 10. The various parts of the assembly are simple and inexpensive of manufacture. The slots 11 may be cored in the bushing 10 and the slips 12 do not require special machining. The liners 25 of the slips 12 may be sections of strips or long stock of the desired cross section and are very inexpensive to manufacture.

The form of the invention illustrated in Figs. 6 to 9, inclusive, of the drawings includes, generally, a master bushing 50 having internal slots 51, slips 52 for arrangement in the slots 51 to grip a pipe P or the like and means 53 for preventing displacement of the slips and for supporting the slips 52 when they are moved to positions at the upper ends of the slots 51.

The bushing 50 is intended for arrangement in the opening of a rotary table. The bushing 50 may be shaped for arrangement in the table T illustrated in Fig. 1 of the drawings or may be polygonal or square, as illustrated in Figs. 6 and 9 of the drawings for arrangement in a typical rotary table. It is to be understood that the bushing 50 is adapted to be supported in a rotary table to be driven or rotated thereby. A central vertical opening 54 is provided in the bushing 50 to pass the pipe P and other drilling equipment. In accordance with the form of the invention being described the opening 54 is polygonal or square in cross section. The opening 54 may be round or cylindrical if desired. The opening 54 is of uniform width or dimensions throughout its length, having vertical walls. This is important as it permits the easy free passage of the drilling equipment through the bushing 50. The bushing 50 is preferably sectional for ready

assembling in a rotary table. As shown in the drawings the bushing 50 preferably includes two sections M and N. The bushing 50 is preferably divided or separated in a vertical plane which intersects two side walls of the opening 54. In the preferred construction the slots 51 for receiving the slips 52 occur in the corners of the openings 54. The slots 51 are preferably alike in size and shape and there may be one slot 51 in each corner of the opening 54. It is to be understood that the invention contemplates the provision of two or more slots 51 in the bushing opening 54. In the form of the invention being described the slots 51 are polygonal or flat walled. The side walls of the slots 51 are flat and vertical and lie in planes tangent to a circle concentric with the central longitudinal axis of the opening 54. The parallel relationship and, therefore, the uniform spacing of the side walls of the slots 51 continues throughout the entire lengths of the slots. The slots 51 may extend between the upper and lower ends of the bushing 50. The innermost walls or inner walls 55 of the slots 51 are flat and are inclined downwardly and inwardly. Curved or inclined surfaces 56 join the upper ends of the slots 51 to assist in entering or guiding the slips 52 into the slots.

The slips 52 are adapted to be inserted in the slots 51 to grip and suspend the pipe P or other object. The several slips 52 are alike and there is preferably a slip 52 provided for each slot 51. The slips 52 are shaped to properly fit the slots 51 having flat parallel sides 57 and downwardly and inwardly inclined rear surfaces 58 for shiftably bearing on the inclined walls 55 of the slots. The slips 52 are preferably proportioned to have proper play or clearance in the slots 51. The active sides of the slips 52 are preferably vertical and if desired teeth or gripping parts may be formed directly on the slips to cooperate with the pipe P. It is preferred, however, to provide replaceable shoes or liners 59 on the slips 52 for gripping the pipe P. The slips 52 are shaped to receive the liners 59 having vertical channels or grooves 60 which terminate at their lower ends in downwardly and outwardly inclined walls 61. Tongues or keys 62 are provided on the liners 59 to fit the grooves 60 to form positive driving connections between the liners and slips. The lower ends of the keys 62 are inclined downwardly and outwardly to have locking cooperation with the groove walls 61.

Means is provided for removably attaching the liners 59 to the slips 52. Rivets or rods 63 are passing through transverse openings in the slips and keys 62 to secure the liners 59 to the slips. The opposite ends of the rods 63 may be headed or riveted. The active faces of the liners 59 are cylindrically concaved to conform, generally, to the pipe P and are provided with suitable wickers or teeth 64. The teeth 64 preferably face upwardly and inwardly and may be interrupted by vertical grooves to have more efficient engagement with the pipe. The liners 59 may be replaced by liners of various thicknesses to adapt the slips 52 for the proper handling of pipe and other objects of various diameters. The bodies of the slips 52 may be chambered or hollowed to be light in weight. Reinforcing webs 65 may extend through the hollow interiors of the slips. Handles H¹ are provided on the slips 52 to facilitate the manipulation of the slips. The handles H¹ may be identical with the handles H described above and reference

is hereby made to the detailed description of the handles H. Corresponding reference numerals are employed to designate corresponding parts of the handles H and H¹ and their mountings.

The means 53 is provided to prevent loss or displacement of the slips 52 from the slots 51 and to assist in supporting the slips in retracted or inoperative positions at the upper ends of the slots. The means 53 comprises elongate grooves or slots 70 in the side walls of the slip 10 receiving slots 51. There may be a slot 70 in each side wall of each slot 51. The slots 70 are parallel with the inclined inner walls 55 of the slots 51 and terminate some distance above the lower ends of the slots 51. Lugs or pins 71 project from the sides of the slips 52 to shiftably operate in the slots 70. The cooperation of the pins 71 with the slots 70 is such that the slips 52 may properly work and shift in the bushing slots 51. The pins 71 are adapted to cooperate with the lower ends of the slots 70 to definitely limit the downward travel of the slips 52 and thus prevent the loss of the slips from the bushing 50. The upper ends of the slots 70 are spaced some distance below the upper end of the bushing 50. The slots 70 and the pins 71 are related so that the pins cooperate with the upper ends of the slots 70 when the slips 52 are brought to positions where they may be pivoted onto the surface 56. The cooperation of the pins 71 with the upper ends of the slots 70 assists in retaining or supporting the slips 52 in their up or inoperative positions on the surfaces 56. Fig. 7 of the drawings illustrates in broken lines a slip 52 in its retracted position where it rests on the surface 56 with the pins 71 in cooperation with the upper ends of the slots 70. In practice removable plates 73 may be recessed or countersunk in the upper ends of the bushing 50 to close the upper ends of the slots 70. The plates 73 thus form the upper ends or walls of the slots 70 and may be removably secured to the bushing by screws or other suitable means. The plates 73 are removable to permit the entrance of the pins 71 in the slots 70 when the slips 52 are assembled in the bushing 50 and are removable to permit the withdrawal of the pins 71 from the slots 70 when the slips are to be removed from the bushing.

It is to be understood that the invention contemplates the embodiment of cradles similar to the cradles 53 described above, in the form of the invention illustrated in Figs. 6 to 9, inclusive, of the drawings, in substitution for the means 53 just described, and contemplates the embodiment of the means 53 in the form of the invention illustrated in Figs. 1 to 5, inclusive, of the drawings in substitution for the cradles 13.

The use or operation of the assembly illustrated in Figs. 6 to 9, inclusive, of the drawings is substantially the same as the operation of the previously described form of the invention. The slips 52 may be easily passed downwardly into the slots 51 to contact and grip the pipe P. The handles H¹ facilitate the lowering of the slips and the pins 71 cooperating with the slots 70 effectively enter the lower ends of the slips in the slots 51 their rear surfaces 58 contact the inner walls 55 of the slots 51 and this engagement urges the slips inwardly against the pipe P. Thus the slips 52 obtain firm dependable gripping contact with the pipe P. The rear sides 58 of the slips 52 are adapted to have full or extensive cooperation with the inner walls 55 of the slots 75

51 regardless of the vertical positions assumed by the slips when they contact or grip the pipe. Accordingly, the slips 52 assume equal loads in suspending or engaging the pipe. The flat sided 5 slips 52 fitting in the flat sided slots 51 cannot possibly tilt or turn and are adapted to form positive effective drives in the event it is desired to rotate the pipe. The liners 59 are operable to obtain firm dependable gripping engagement with the pipe P without subjecting the bodies of the slips proper to wear. When the slips 52 are no longer required to grip the pipe P they may be easily and quickly removed from the slots 51. The slips 52 may be easily pulled upwardly from the slots to positions where they are supported on the surfaces 56 with their pins 11 bearing on the plates 73 which form the upper walls of the slots 70. The cooperation of the pins 11 with the upper ends of the slots 70 operates to retain the 10 slips in their inactive positions on the surfaces 56. The bushings 50 and the slips 52 are simple and easy to manufacture. The slots 51 may be cored directly in the sections of the bushing 50 and the slips 52 do not require extensive machining. The 15 liners 59 may be easily replaced to recondition the slips 52 or to adapt the slips for the engagement of pipes of different diameters.

Fig. 10 of the drawings illustrates a form of the invention embodying a master bushing 80 comprising two unequal sections X and Y. The bushings 80 may be of the same configuration as the bushing 10 or the bushing 50. In the particular case illustrated the bushing 80 is of the same general configuration as the bushing 50. 20 The polygonal opening 81 of the bushing 80 has flat walled slots 82 in its corners for receiving slips 83. The slips 83 may be identical with the slips 52. The bushing 80 is divided into the two sections X and Y in a vertical plane 85 spaced from the central longitudinal axis of its opening 81. The line or plane 85 of division of the bushing 80 preferably angularly intersects two adjacent sides of the polygonal opening 81. When the bushing 80 is divided in this manner one section 25 X has three slots 82 while the other section Y has one slot 82. Where the one section X carries three slips 83 the bushing 80 cannot spread or work and a very positive suspension or gripping engagement with the pipe P is obtained. The 30 operation and the mode of handling the slips 83 are the same as described above in connection with the slips 52.

When I use the term "liner" I refer to the shoe or shoe-like part that actually engages the pipe or the object handled.

Having described only typical preferred forms and applications of my invention, I do not wish to be limited or restricted to the specific details herein set forth, but wish to reserve to myself any variations or modifications that may appear to those skilled in the art or fall within the scope of the following claims:

Having described my invention, I claim:

1. A bushing for a rotary table comprising a body having a polygonal opening of unvarying width, and having slots in the walls of the opening for receiving slips.

2. In combination, a bushing for a rotary table having a polygonal opening for receiving a piece of drilling equipment, and having longitudinal slots in the corners of the opening, said slots having inclined walls, and slips arranged in the slots to grip the piece of equipment and having inclined surfaces cooperating with said walls.

3. In combination, a bushing for a rotary table

having a polygonal opening for receiving a piece of drilling equipment, and having longitudinal slots in the corners of the opening, said slots having substantially parallel side walls and downwardly and inwardly inclined inner walls, and slips shiftably fitting the slots to grip the piece of equipment.

4. In combination, a bushing for a rotary table having an opening for receiving a piece of drilling equipment, and having spaced slots in the wall of the opening provided with parallel side walls and cylindrically concaved inner walls, and slips in the slots for engaging the piece of equipment and having parallel sides and cylindrically convex rear sides for cooperating with the walls of the slots.

5. A slip for arrangement in a rotary table bushing comprising a slip body having substantially parallel sides, and a downwardly and inwardly inclined rear surface, and means projecting from the lower end of the slip body for guiding it in a slot in the bushing.

6. A slip for arrangement in a rotary table bushing comprising a slip body having substantially parallel sides, and a cylindrically curved downwardly and inwardly inclined rear surface extending between said sides, and means on the active face of the slip body for engaging an object extending through the bushing.

7. A master bushing comprising a body having a polygonal opening with substantially vertical walls, and having substantially vertical slots in the corners of the opening, said slots having substantially parallel side walls and inclined inner walls.

8. A master bushing comprising a body having an opening with a cylindrically curved wall, and having spaced vertical slots in the wall of the opening, said slots having substantially parallel side walls and inclined inner walls.

9. Apparatus of the character described comprising a master bushing having a polygonal opening with substantially vertical walls and having substantially vertical slots in the corners of the opening, said slots having substantially parallel side walls and inclined inner walls, and slips arranged in the slots to grip an object extending through the opening, the slips having substantially parallel sides and inclined surfaces for cooperating with the inclined walls of the slots.

10. Apparatus of the character described including a master bushing for a rotary table, the bushing having an opening for passing drilling equipment and slots in the wall of the opening, gripping slips adapted for insertion in the slots, and stationary cradles carrying the slips for ready entrance to the slots.

11. Apparatus of the character described including a master bushing for a rotary table, the bushing having an opening for passing drilling equipment and slots in the wall of the opening, gripping slips adapted for insertion in the slots, stationary cradles on the upper side of the bushing for supporting the slips in radial alignment with the slot for insertion therein.

12. Apparatus of the character described including a master bushing for a rotary table, the bushing having an opening for passing drilling equipment and slots in the wall of the opening, gripping slips adapted for insertion in the slots, handles on the slips, cradles for supporting the slips above the openings, and parts on the cradles cooperable with the handles to releasably retain the slips on the cradles.

13. In combination with a rotary table bushing

and a slip for use therein, a cradle for supporting the slip comprising a support to be mounted on the bushing, and a saddle on the support for carrying the slip.

5 14. In combination with a rotary table bushing and a slip for use therein, a cradle for supporting the slip comprising a support to be mounted on the bushing, and a saddle on the support having a concave surface inclined downwardly and inwardly toward the opening of the bushing to receive the slip.

10 15. In combination with a rotary table bushing, a slip for use in the bushing, a handle on the slip, a support on the bushing, a saddle on the support for carrying the slip, and a fork on the support engageable by the handle to retain the slip in the saddle.

15 16. A rotary table bushing comprising a body having a vertical opening and circumferentially spaced slots in the wall of the bushing, the body being divided in a vertical plane spaced from the central axis of the opening to comprise two sections, one of said sections having more slots than the other.

17. In combination, a rotary table bushing having an opening for passing drilling equipment, there being a slot in the wall of the opening having an inclined inner wall, and a groove in a side wall of the slot substantially parallel with said inclined wall, a seat at the upper end of the slot, a slip shiftable in the slot operable to engage an object in the opening and shiftable to a retracted position on the seat, and a projection on the slip operable in the groove and cooperable with the upper end of the groove to retain the slip on the seat. 5

18. In combination, a rotary table bushing having an opening for passing drilling equipment, there being a slot in the wall of the opening having an inclined inner wall, and a groove in a side wall of the slot substantially parallel with said inclined wall, a slip shiftable in the slot operable to engage an object extending through the opening, and a projection on the slip 10 operating in said groove to prevent displacement of the slip from the slot. 10
